US0D1038808S

(12) **United States Design Patent** (10) **Patent No.:** **US D1,038,808 S**
Chen et al. (45) **Date of Patent:** **** Aug. 13, 2024**

(54) **HOLDER FOR A WEARABLE DEVICE**

- (71) Applicant: **META PLATFORMS TECHNOLOGIES, LLC**, Menlo Park, CA (US)
- (72) Inventors: **Chunli Chen**, Seattle, WA (US); **Derek William Wright**, San Francisco, CA (US); **Peter Wesley Bristol**, Seattle, WA (US)

- (73) Assignee: **Meta Platforms Technologies, LLC**, Menlo Park, CA (US)

(**) Term: **15 Years**

(21) Appl. No.: **29/770,239**

(22) Filed: **Feb. 10, 2021**

(51) LOC (14) Cl. **10-07**

(52) U.S. Cl.

(57) **CLAIM**

The ornamental design for a holder for a wearable device, as shown and described.

DESCRIPTION

FIG. 1 is a perspective view of holder for a wearable device showing the claimed design;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The oblique shade lines in the figures show a reflective or shiny surface, and not surface ornamentation.

1 Claim, 7 Drawing Sheets
